UNITED STATES PATENT OFFICE.

JOHN T. BEECHLYN, OF LYNN, MASSACHUSETTS, ASSIGNOR TO GENERAL ELECTRIC COMPANY, A CORPORATION OF NEW YORK.

ARC-LAMP.

1,218,509.

Specification of Letters Patent.

Patented Mar. 6, 1917.

Application filed May 8, 1912. Serial No. 695,831.

To all whom it may concern:

Be it known that I, JOHN T. BEECHLYN, a citizen of the United States, residing at Lynn, county of Essex, State of Massachusetts, have invented certain new and useful improvements in Arc-Lamps, of which the following is a specification.

My invention has reference to an arc lamp of the focusing type.

10 Focusing lamps have heretofore been made, in which the electrodes are caused to advance toward or recede from each other in step by connecting them together by means of a flexible connection passing over 15 a pulley. In such an arrangement the arc is established by a movement of both of the electrodes away from each other, and is subsequently regulated by a movement of both of the electrodes in response to variations 20 of current in the arc. In such a lamp, however, on account of the inertia of the two electrodes and of the connected parts and on account of friction, the moving parts do not quickly respond to variations in current, 25 which results in a sluggish and unsatisfactory regulation. I have overcome this defect by a novel arrangement whereby the regulation of the arc is effected by but one of the electrodes, while both of the electrodes are intermittently fed toward each other. In this way but a single electrode is involved in the regulation, and the inertia of the moving parts is, therefore, small as compared with the ordinary focusing 35 lamp, in which both of the electrodes must be moved to effect the regulation. At the same time, since both of the electrodes are moved toward each other in the feeding operation, the arc is kept focused.

40 I have illustrated my invention in the accompanying drawings, in which Figure 1 is a skeleton of my lamp, showing the operating parts and the electrical connections; Fig. 2 is a detail view of the counterweight 45 for the lower electrode; Fig. 3 is a detail horizontal section along line 3—3 Fig. 2, and Fig. 4 is a perspective view of the counterweight.

In the drawings, 1 is the top plate of the 50 lamp. A bottom plate 2 is secured to the plate 1 by spacing bars 3 and 4. A cup shaped member 5 having cylindrical walls is seated against the under side of an insulating plate 6 which separates the member 5 from the plate 2. The upper and

lower electrodes are indicated by the numerals 7 and 8 respectively. The upper electrode 7 is carried by a suitable holder 9, which is in turn secured to a rod 10 guided by a sleeve 11 upstanding from the plate 1. 60 The electromagnet 12, the mounting for which is not shown, is provided with a U-shaped armature 13 which carries a clutch 14, embracing the rod 10. The armature is provided with an upstanding bar 15 to which is secured a cross piece 16. To the ends of this cross piece are pivoted stems 17 secured to the cylinders 18 of two dash pots, the pistons 19 of which are carried by the plate 1. The lower electrode 8 70 is received within a socket 20 carried by a cross arm 21, the ends of which are guided within slots 22' in tubes 22 secured to the bottom plate 2. One end of the cross arm 21 is secured to a rod 23 which passes longitudinally through one of the members 22 and through the chamber formed by the two parts 2 and 5. To the upper end of the rod 23 is attached a chain or other flexible connection 24 which passes over a pulley 25. 80 The other end of the chain 24 is connected to a counterweight 26. This counterweight comprises a casing 27 closed by a plate 28 (Fig. 4) and a member 29 projects laterally from the casing. The ends of the 85 casing are provided with openings 30 in which are received lugs 31 projecting inwardly from the plate, thus partially filling the openings 30 and leaving smaller openings 32 through which the spacing bar 3 is 90 adapted to pass. The outer end of the member 29 is formed into a ring and is provided with an opening 33 in which is received the enlarged lower end 34 of the rod 10. The extreme outer end of the member 29 is formed into a finger 35 which is received in a slot 4^a in the spacing rod 4. 95

The counterweight 26 and the parts connected thereto are so proportioned with reference to the weight of the lower electrode as to move the latter upwardly when the counterweight is free to move. The counterweight is normally restrained, however, by a clutch 36 which is an arm, one end of which passes through a slot 37 in 105 the side of the casing 27, while its opposite end embraces the rod 3. An upwardly extending stem 38 is secured to the clutch 36 by a pin 39. The upper reduced portion of stem 38 passes along and engages one 110

edge of a block 40, which is pivoted at 41. This block is provided with a tripping arm 42 which extends laterally through a wide opening 43 in the casing to a point beneath a plate 44, secured to the upper end of the 5 enlarged portion 34 of the rod 10. The inner end of the clutch 36 is urged upwardly by a spring 45 located between the clutch and the bottom of the casing 27, the upper end of slot 37 serving as a pivot to the clutch, and when the arm 42 is free to move in the opening 43 the spring lifts the clutch and the connected parts into the position shown in Fig. 1, the reduced upper 10 end of stem 38 gently bearing against one edge of the tilting block 40, in which position the clutch 36 engages and binds the rod 3 and prevents descent of the counterweight 26 and the raising of the lower electrode. 15 The electrical connections for the lamp 20 are indicated in Fig. 1, and as the magnet is simply included in series with the arc in a manner well understood in the art, it is believed that no detailed description of the 25 circuits is necessary.

The operation of my lamp is as follows:—

When the lamp is without current the electrodes are in contact, the parts of the 30 counterweight are in the positions shown in Fig. 2, and the clutch 14 rests upon the sleeve 11. Now when current is turned on, the magnet 12, which is in series with the 35 arc, is energized thereby attracting its armature 13 and lifting the clutch 14 free from the sleeve 11, at the same time gripping the carbon carrying rod 10 and lifting the upper electrode 7 from the lower electrode to establish the arc. At the same time, the 40 plate 44 on the upper end of the member 34 is lifted free from the tripping arm 42, as shown in Fig. 1, and the clutch 36 urged by spring 45 binds the counterweight to rod 3, while the upper electrode is free to move. 45 The magnet then regulates the arc by the movement of the upper electrode only in response to variations of current in the arc, in a well known manner. As the electrodes are consumed, the arc tends to lengthen and 50 the upper electrode 7 and the connected parts descend until plate 44 engages the tripping arm 42. When this takes place, the block 40 is tilted about the pivot 41, thereby forcing the upper end of the stem 55 38 inwardly toward the rod 34 and lowering the inner end of the clutch 36. The clutch is thereby made to release its hold upon the spacing rod 3 and the counterweight 26 is permitted to descend and to 60 move upwardly the lower electrode 8, the upper electrode being free to descend correspondingly, thereby maintaining the arc at substantially the same point. As soon as 65 the lower electrode is moved upwardly a small amount and the upper electrode makes

its corresponding downward movement, the current in the arc and therefore in the operating magnet is increased, when the upper electrode will be again lifted and the plate 44 is removed from the tripping stem 70 42, the magnet thus regulating the movement of the upper electrode, that is to say the length of the arc, in the same manner as before. It will be understood that when the upper electrode is consumed to such an 75 extent as to cause the clutch 14 to come into engagement with the sleeve 11, the clutch will be tripped in the usual manner, thus causing the clutch 14 to grip the rod 10 at a new point.

What I claim as new and desire to secure by Letters Patent of the United States, is:—

1. In an arc lamp, a pair of electrodes, means for regulating the arc by the movement of a single electrode, and means for 85 feeding together both electrodes.

2. In an arc lamp, a pair of vertically aligned electrodes, means for moving the upper electrode away from the lower and independently of the lower to establish the 90 arc and for freely regulating the same, and means responsive to a predetermined movement of the upper electrode toward the lower for causing both electrodes to approach each other.

3. In an arc lamp, a pair of vertically aligned electrodes, means for moving the upper electrode away from the lower and independently of the lower to establish the 100 arc and for freely regulating the same, a normally restrained counterweight for causing the electrodes to move together in step, and means responsive to the movement of the upper electrode toward the lower for releasing the counterweight.

4. In an arc lamp, a pair of vertically aligned electrodes, means for moving the upper electrode away from the lower and independently of the lower to establish the 110 arc and for freely regulating the same, means comprising a counterweight for moving both electrodes toward each other, and a clutch normally restraining the movement of the counterweight which is adapted to be released by the movement of the upper electrode 115 toward the lower.

5. In an arc lamp, a pair of vertically aligned electrodes, means for moving the upper electrode away from the lower and independently of the lower to establish the 120 arc and for freely regulating the same, a counterweight for moving both electrodes toward each other, a clutch associated with said counterweight to normally restrain the same, and a tripping device movable with 125 the upper electrode for tripping said clutch after the upper electrode has moved toward the lower a predetermined distance.

6. In an arc lamp, a pair of vertically aligned electrodes, electromagnetic means for 130

- lifting the upper electrode from the lower to establish the arc and for freely regulating the same, means comprising a counterweight movable along and guided by a pair of parallel rods for intermittently moving the electrodes toward each other, a clutch associated with the counterweight for normally gripping one of the parallel rods, and means responsive to the movement of the upper electrode for intermittently tripping said clutch.
7. In an arc lamp, a pair of vertically aligned electrodes, electromagnetic means for lifting the upper electrode from the lower to establish the arc and for freely regulating the same, means comprising a counterweight movable along and guided by a pair of parallel rods for intermittently moving the two electrodes toward each other, a clutch associated with the counterweight for normally gripping one of the parallel rods, and means responsive to the movement of the upper electrode toward the lower for tripping said clutch.
- 15 8. In an arc lamp, a pair of vertically aligned electrodes, electromagnetic means for lifting the upper electrode independently of the lower to establish the arc and for freely regulating the same, a downwardly movable counterweight, connections between the counterweight and the lower electrode for moving said lower electrode upwardly when the counterweight moves downwardly, means associated with the counterweight for normally restraining the same from movement, and means movable in accordance with the movement of the upper electrode for releasing said restraining means when the upper electrode has moved toward the lower electrode a predetermined distance.
- 25 9. In an arc lamp, a pair of vertically aligned electrodes, means for moving the upper electrode away from the lower and independently of the lower to establish the arc and for freely regulating the same, and
- means responsive to a predetermined movement of the upper electrode toward the lower for causing both of the electrodes to approach each other.
10. In an arc lamp, a pair of coöperating electrodes, means for connecting the electrodes together so that they feed together in step, means for rendering one of said electrodes free from said connecting means whereby the same may be moved away from the other electrode to establish the arc and then moved in accordance with the arc requirements, and means releasable in response to the movement of said regulating electrode for restraining the movement of the second electrode during the regulating action of the first electrode.
- 15 11. In an arc lamp, a pair of axially aligned electrodes, means for connecting the electrodes so that they move together in step, said means comprising a lost motion connection with the upper electrode, means for moving said upper electrode away from the second to establish the arc and for subsequently regulating the same, means for restraining the movement of the second electrode during the regulation of the first and for releasing the same when the lost motion is exhausted whereby the two electrodes then move together in step.
- 20 12. In an arc lamp, a pair of aligned electrodes, means for normally restraining the movement of one of the electrodes, means for moving the second electrode independently of the first, and means responsive to a predetermined movement of the second electrode for releasing the first electrode and for then causing both electrodes to approach each other.
- 25 In witness whereof, I have hereunto set my hand this sixth day of May, 1912.
